(57) **CLAIM**

I claim the ornamental design for a disposable liner for an animal litter box, as shown and described.

DESCRIPTION

FIG. 1 is a perspective view of a first embodiment of a disposable liner for an animal litter box, showing my new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a top plan view thereof, shown in a collapsed configuration.

FIG. 9 is a bottom plan view thereof, shown in a collapsed configuration.

FIG. 10 is a perspective view of a second embodiment of a disposable liner for an animal litter box, showing my new design.

FIG. 11 is a bottom plan view thereof.

FIG. 12 is a front elevation view thereof.

FIG. 13 is a rear elevation view thereof; and,

FIG. 14 is a bottom plan view thereof, shown in a collapsed configuration.

The broken lines in the drawings illustrate portions of the disposable liner for an animal litter box that form no part of the claimed design. The diagonal sinuous lines in the drawings indicate surfaces of the disposable liner for an animal litter box that are formed of a flexible material.
